UNITED STATES PATENT OFFICE.

FRED HENRY ROBERTS, OF WILMINGTON, MASSACHUSETTS.

DESIGN FOR A CANDY-DISPLAY TRAY.

SPECIFICATION forming part of Design No. 36,916, dated May 17, 1904.

Application filed April 15, 1904. Serial No. 203,378. Term of patent 14 years.

To all whom it may concern:

Be it known that I, FRED HENRY ROBERTS, a citizen of the United States, residing at Wilmington, in the county of Middlesex and State 5 of Massachusetts, have invented a new, original, and ornamental Design for a Candy-Display Tray, of which the following is a specification.

The design is shown in perspective in the accompanying drawing.

Having shown my invention, what I claim as new, and desire to secure by Letters Patent of the United States, is—

The ornamental design for a candy-display tray as shown.

FRED HENRY ROBERTS.
